UNITED STATES PATENT OFFICE.

JOHN B. RUSS, OF SHELTON, CONNECTICUT.

WEBBING BUCKLE.

Application filed May 15, 1928. Serial No. 277,866.

My invention relates to webbing buckles for garters, suspenders and the like and has for its object to provide a new and improved webbing buckle having a wire link provided with new and improved means for securing the webbing thereto.

The following is a description of my invention, reference being had to the accompanying drawings, in which,

10 Fig. 1 shows a portion of a garter comprising a buckle embodying my invention;

Fig. 2 is a cross-section of the buckle with the webbing adjacent thereto on the line 2—2, Fig. 1;

15 Fig. 3 is a side elevation of the same;

Fig. 4 is a front elevation of the buckle of Fig. 1 with the clamping lever raised;

Fig. 5 is a detail section on the line 5—5, Fig. 4;

20 Figs. 6, 7, 8 and 9 are front elevations of modifications of the link and web securing means applied thereto.

Referring more particularly to the drawings, 2 is a buckle embodying my invention applied to a webbing 4 which carries at its lower end a loop 6. The buckle is composed of a wire link 8 which may be open at one end, the other end of the link having a cross-bar 10 and vertically extending side arms 12.

30 Upon the top portion of the link a lever clamp 14 having clamping teeth 16 is pivotally mounted by trunnions 18. 20 is a web securing plate having lateral extensions 22 which embrace the side portions 12 so as to secure 35 the plate to those portions. This plate is provided on its front side with an upturned portion 24, provided with teeth 26 for securing the webbing to the plate. The body portion of the plate extends upwardly as far as

40 the top of the upturned portion 24 and preferably a little higher, as shown. One end of the webbing is placed between the body portion of the plate and the upturned portion 24 and the plate is then swaged upon the web-

45 bing, as shown in Fig. 2, gripping it so as to hold it firmly in place. The portions 12 are provided at their ends with laterally turned ends 28 which prevent the plate 20 from sliding off them. In the form shown in Fig. 1

50 its laterally turned portions extend inwardly and are beneath the plate 20 so as to lie in its

path. In forming this buckle the links 8 are first formed and then the lever clamp 12 and plate 20 are mounted thereon by bending extensions on the lever clamp so as to form the 55 trunnions 18 and binding the extensions on the plates so as to form the embracing portions 22. The end of the webbing is then secured to the plate by swaging the portion 24 so as to form a web gripping socket with the 60 body of the plate. The webbing passes over the top of the body portion 20 of the plate, which is at least as high as the top of the teeth 26, and then is passed downward behind the plate 20 through the loop 6 and upward in 65 front of the portion 24 and through the link again, as shown in Figs. 2 and 3.

The sides of the link are bent in their medial portions, i. e., intermediate between their ends, so that the top of the link lies in a position slightly forward of the plane of the lower portions of the side portions. The body and upturned portion of the plate are substantially parallel to the plane of the lower parts of the depending portions of the link. 75

With this constriction the upwardly extending reach of the webbing is clamped against the portion of the webbing lying above the top of the body of the plate 20. The extreme end of the webbing lies within portions of the plate 20 and between the depending portions of the link, so that although the buckle is one which clamps webbing against webbing, the thickness of the buckle is only that resulting from the link and two thicknesses of webbing and the lever of the clamp. The buckle is simple to manufacture and while strong and durable is thin, and, furthermore, clamps the webbing securely in any position in which it is adjusted. 85

In the modification shown in Fig. 6, 8' constitutes the link and 20' the plate. In this case the lateral extensions 28 of Fig. 4 lying beneath the plate 20 are omitted and in lieu thereof the embracing portions of the plate 90 and the underlying parts of the downward projections 12 are swaged at 30 so as to hold the plate to the link.

In Fig. 7 the link 8' has its lower end portions inclined inwardly at an angle and the 100 plate 20' has its lateral extension 22' bent around those inclined portions, the inclina-

tions on the depending parts preventing the plate from slipping off the ends of the link.

In the form shown in Fig. 8 the link 8³ is a closed link and the plate 20³ surrounds the 5 lower limb of the link having lateral extensions 22³ embracing the depending portions which are held against downward movement by the lower limb of the link.

In the form shown in Fig. 9 the link 8⁴ has 10 depending portions which at their lower ends are inclined outwardly and are surrounded by lateral extensions 22⁴ on the plate, the inclined portions in this case also preventing the plate from slipping off the link.

15 As will be evident to those skilled in the art, my invention permits of various modifications without departing from the spirit thereof or the scope of the appended claims.

What I claim is:

20 1. In a device of the character described, a base comprising a link having a cross-bar and side portions extending vertically from the ends thereof, a plate having lateral projections embracing said side portions and thereby secured to said link, said plate having an upturned portion forming a web-gripping socket with the body of the plate, and a clamping member pivotally mounted on the upper portion of said link.

25 2. In a device of the character described, a base comprising a link having a cross-bar and side portions extending vertically from the ends thereof, a plate having lateral projections embracing said side portions and thereby secured to said link, said plate having an upturned portion forming a web-gripping socket with the body of the plate, and a clamping member pivotally mounted on the upper portion of said link, said upturned portion 30 being on the front side of said plate.

35 3. In a device of the character described, a base comprising a link having a cross-bar and side portions extending vertically from the ends thereof, a plate having lateral projections embracing said side portions and thereby secured to said link, said plate having an upturned portion forming a web-gripping socket with the body of the plate, and a clamping member pivotally mounted on the upper portion of said link, said side portions being 40 forwardly bent at points intermediate their ends.

45 4. In a device of the character described, a base comprising a link having a top cross-bar and portions depending from the ends thereof, the lower parts of said depending portions being bent sidewise, a plate having lateral projections embracing said depending portions and thereby secured to said link, said plate having an upturned portion 50 forming a web-gripping socket with the body of the plate, and a clamping member pivotally mounted on said top cross-bar.

55 5. In a device of the character described, a base comprising a link having a top cross-

bar and side portions depending from the ends thereof, the lower ends of said depending portions being bent inwardly, a plate having lateral projections embracing said depending portions and engaging said inwardly bent portions and thereby secured to said link, said plate having an upturned portion forming a web-gripping socket with the body of the plate, and a clamping member pivotally mounted on said top cross-bar. 70

6. In a device of the character described, a base comprising a link having a top cross-bar and side portions depending from the ends thereof, a plate having lateral projections embracing said depending portions and thereby secured to said link, said plate having an upturned portion forming a web-gripping socket with the body of the plate, and a clamping member pivotally mounted on 80 said top cross-bar, the lower ends of said depending portions being bent inwardly and extending below and engaging said lateral projections.

7. In a device of the character described, a base comprising a link having a top cross-bar and portions depending from the ends thereof, a plate having lateral projections embracing said depending portions and thereby secured to said link, said plate having an upturned portion forming a web-gripping socket with the body of the plate, and a clamping member pivotally mounted on said top cross-bar, the lower ends of said depending portions being bent inwardly and extending below and engaging said lateral projections 90

95 and said plate.

8. In a device of the character described, a link having a cross-bar and side portions extending vertically from the ends thereof, a plate having lateral projections embracing said side portions and thereby secured to said link, said plate having an upturned portion forming a web-gripping socket with the body of the plate, and a clamping member pivotally mounted on the upper portion of 100 said link, said side portions being forwardly bent at points intermediate their ends, the body and upturned portion of said plate being substantially parallel to the plane of the lower parts of said side portions. 105

9. In a device of the character described, a link having a cross-bar and side portions extending vertically from the ends thereof, a plate having lateral projections embracing said side portions and thereby secured to said link, said plate having a forwardly upturned portion forming a web-gripping socket with the body of the plate, and a clamping member pivotally mounted on said top cross-bar, the body of said plate extending upward at least 110 as far as the top of its said upturned portion. 115

10. In a device of the character described, a link having a cross-bar and side portions extending vertically from the ends thereof, a plate having lateral projections embracing 120

said side portions and thereby secured to said link, said plate having an upturned portion forming a web-gripping socket with the body of the plate, said upturned portion being on the front side of said plate, a clamping member pivotally mounted on the upper portion of said link, and a webbing held against the body of said plate by said upturned portion and passing through said link and downwardly behind said plate and then upwardly 10 in front of said plate and again through said link and beneath said clamp.

In testimony whereof, I have signed my name to this specification this 11th day of May, 1928.

JOHN B. RUSS.
